United States Patent Office.

JOHN T. GROSE, OF UPPER SANDUSKY, OHIO, ASSIGNOR TO HIMSELF AND
WILLIAM E. KINNEAR, OF SAME PLACE.

Letters Patent No. 98,585, dated January 4, 1870.

IMPROVEMENT IN WASHING-APPARATUS.

The Schedule referred to in these Letters Patent and making part of the same.

To all whom it may concern:

Be it known that I, JOHN T. GROSE, of Upper Sandusky, in the county of Wyandot, and State of Ohio, have invented a new and improved Steam Washing-Apparatus; and I do hereby declare that the following is a full, clear, and exact description thereof, which will enable others skilled in the art to make and use the same, reference being had to the accompanying drawings, forming part of this specification, in which—

Figure 1 is a detail vertical section of my improved machine, taken through the line $x x$ of fig. 2.

Figure 2 is a detail vertical section of the same, taken through the line $y y$, fig. 1.

Similar letters of reference indicate corresponding parts.

My invention has for its object to furnish a simple, convenient, and efficient machine, by which the clothes will be quickly and thoroughly washed by the circulation of steam and hot water, and which shall be so constructed as to allow the dirty water to be drawn off and replaced with clean hot water when desired; and

It consists in the arrangement of the various parts of the apparatus as hereinafter more fully described.

A is a furnace, which I prefer to make conical, but which may be made of any other convenient form, and which is surrounded with a boiler, B, in which the water is heated.

Fuel is introduced into the furnace A, through an opening, a^1 , in its upper part, above the boiler B, as shown in figs. 1 and 2.

C are two pipes, leading out from the lower part of the boiler B, and which may be connected with said boiler separately, or with a single connection-pipe, as shown in fig. 2.

The pipes C are provided with stop-cocks c' , so that the water may be allowed to circulate through both, either, or neither of said pipes, as may be desired.

The upper ends of the pipe C are securely connected with the bottoms of the wash-tubs D, or other receiving-vessels.

The pipes C should be made in two parts coupled together, so that the tubs D may be detached, and replaced with steamers for steaming food for cattle, hogs, &c., or with other vessels, according to the purpose for which the apparatus is to be used.

E are two pipes, the lower ends of which are connected with the upper part of the boiler B, either separately or by a single connecting-pipe, as may be desired. The upper ends of the pipes E are connected with the bottoms of the vessels D, preferably with the middle part of said bottoms, as shown in fig. 2.

The pipes E are provided with stop-cocks e' , so that the water or steam may be allowed to circulate through both, either, or neither of said pipes, as may be desired.

The furnace A is provided with a smoke-pipe, a^2 , in the ordinary manner, and the boiler B is provided with a faucet, b' , through which the water contained in it may be drawn off when required.

The tub D, into which the clothes are placed to be washed, is provided with a steam-pipe, F, the upper end of which is enlarged or has a close cap or head, f^1 , with a cone-shaped top attached to it, from the bottom of which, six small tubes or pipes f^2 project downward around the body of the pipe F, as shown in figs. 1 and 2, so that the steam and water may be projected upon all parts of the clothes placed in the said tub around the said pipe F.

The base f^3 of the pipe F is made with shallow scallops around its edge, and with angular depressions around each scallop, the parts of the edge between the scallops being turned down to form feet for the said pipe to stand upon.

By this construction, the water can readily escape from the tub, and flow back into the boiler, to be again heated, and again projected upon the clothes.

In using the apparatus for washing-purposes, one of the tubs or vessels is designed to be used simply as a hot-water reservoir. The stop-cocks in the pipes connecting this tub with the upper and lower parts of the boiler B, being opened, the water is allowed to circulate through the boiler, pipes, and tub or reservoir, until the water in said reservoir has been thoroughly heated. These stop-cocks are then closed and the others opened, allowing the hot water and steam to circulate through the boiler, pipes, pipe F, and the other tub, washing the clothes.

When the water has become dirty, it is drawn off through the faucet b' , and hot water again admitted from the other tub or vessel D, to continue the operation. This construction also allows the clothes to be rinsed without removing them from the tub.

Having thus described my invention,

I claim as new, and desire to secure by Letters Patent—

The arrangement of the tubs D, steam-pipe F, f^1 , f^2 , f^3 , and pipes C and E, with reference to each other and the boiler B and furnace A, substantially as herein shown and described.

JOHN T. GROSE.
